UNITED STATES PATENT OFFICE.

MILTON B. ROLLER, OF SAN FRANCISCO, CALIFORNIA, ASSIGNOR TO THOMAS DAY COMPANY, OF SAN FRANCISCO, CALIFORNIA, A CORPORATION OF CALIFORNIA.

DESIGN FOR A LIGHTING-BRACKET BACK PLATE.

● 61,105.

Specification for Design. Patented June 20, 1922.

Application filed August 1, 1921. Serial No. 489,081. Term of patent 14 years.

To all whom it may concern:

Be it known that I, MILTON B. ROLLER, a citizen of the United States, and a resident of the city and county of San Francisco, State of California, have invented a new, original, and ornamental Design for a Lighting-Bracket Back Plate, of which the following is a specification, reference being had to the accompanying drawings, forming part thereof.

Figure 1 is a front elevation and

Figure 2 is a side elevation of a lighting bracket back plate, respectively illustrating my new design.

I claim:

The ornamental design for a lighting bracket back plate substantially as shown.

MILTON B. ROLLER.
